United States Patent Office

Des. 208,379
Patented Aug. 22, 1967

208,379

JAR

Martin Schnur, West Orange, and Mel Appel, Livingston,
N.J., assignors to American Can Company, New York,
N.Y., a corporation of New Jersey

Filed Dec. 30, 1965, Ser. No. 380

Term of patent 14 years

(Cl. D58—25)

FIG. 2

We claim:

The ornamental design for a jar, as shown.
